UNITED STATES PATENT OFFICE.

CORNELIS F. M. VAN BERKEL, OF LAPORTE, INDIANA, ASSIGNOR TO U. S. SLICING MACHINE COMPANY, OF LAPORTE, INDIANA, A CORPORATION OF INDIANA.

HOLDER FOR SLICING-MACHINES.

1,274,958.

Specification of Letters Patent. Patented Aug. 6, 1918.

Application filed June 27, 1917. Serial No. 177,389.

To all whom it may concern:

Be it known that I, CORNELIS F. M. VAN BERKEL, a subject of the Queen of the Netherlands, and a resident of Laporte, in the county of Laporte and State of Indiana, have invented certain new and useful Improvements in Holders for Slicing-Machines, of which the following is a specification:

- 10 This invention relates to a device for holding meat and similar material while it is being sliced, and is especially adapted for holding such material during the slicing of the last portion of a given piece.
- 15 The objects of the invention are to provide a device of the character named which shall be of improved construction and more efficient and convenient in operation than similar devices previously known.
- 20 The invention is exemplified in the combination and arrangement of parts shown in the accompanying drawings and described in the following specification, and it is more particularly pointed out in the appended claims.

In the drawings—

Figure 1 is a front elevation of a device embodying the present invention;

Fig. 2 is a top plan view of the device shown in Fig. 1;

Fig. 3 is a section on line 3—3 of Fig. 1;

Fig. 4 is a detail of construction;

Fig. 5 is a front elevation of a slightly modified form of the present invention;

Fig. 6 is a top plan view of Fig. 5; and

Fig. 7 is a section on line 7—7 of Fig. 5.

Referring first to Figs. 1 to 4 inclusive, the numeral 10 designates the reciprocating table of a slicing machine of ordinary construction, and 11 is a sliding meat plate mounted upon the table and provided with the usual means for feeding the plate toward the slicing knife after the formation of each slice, the feeding means not being shown in the drawings. The plate 11 has projections 12 and 13 extending from opposite sides of the front edge of the plate, which carry respectively uprights 14 and 15.

50 A rectangular frame having end pieces 16 and 17, a bottom member 18 and a top member 19, is held in place between the uprights 14 and 15 by strap hooks 20 and 21 which may be slid downwardly into position over the uprights. The plates 22 and 23 are se-

cured to the front and rear sides respectively of the bar 19 and extend downwardly as shown in Fig. 3, to form a channel or groove directly beneath the bar. Similar plates 24 and 25 are connected to the lower bar 18 to 60 form a channel along the upper surface of this bar. A series of upright plates 26 are arranged within the open frame and are held in place by the plates 22, 23, 24 and 25, the ends of the plates 26 being positioned within the channels formed adjacent the bars 18 and 19. The plates 26 are arranged with their vertical edges contiguous with one another so that they present a continuous surface when they are all in position.

Each of the plates 26 carries a series of prongs or spikes 27 projecting from the front surfaces of the plates, the prongs of alternating plates being inclined in opposite directions, as shown in the drawing. All of the plates which have their prongs directed downwardly are rigidly secured together by a bar 28 which extends across the back of the frame and is secured to alternate plates 26 by rivets 29. A second bar 30 connects the remaining plates in a similar manner and thus the entire set of plates is divided into two groups, the plates of each group alternating with the plates of the other, and the prongs of each group being inclined in a direction opposite to the prongs of the plates of the other group. The bar 28 has a link 31 pivotally connected to it at 32, and the bar 30 has a similar link 33 secured to it by a pivot 34.

A Y-shaped bracket 35 is connected to the frame of the device by rivets 36, and carries a pivot pin 37 on which is mounted a lever 38. The lever 38 is provided with a cross-arm 39 which has its opposite ends pivotally secured to the ends of the links 31 and 33, as shown at 40 and 41 respectively.

When the handle 38 is shifted in a clockwise direction, as viewed in Fig. 1, the bar 30 will be moved downwardly, and the bar 28 will be moved upwardly, and each bar will carry with it its associated plates 26, thus moving all of the prongs 27 in the direction of their pointed ends. A reverse rotation of the handle 38 will of course move the prongs 27 in the opposite direction. The plates 26 are of such a length that they will always be retained within the channels in which they are mounted but will have suffi-

cient vertical movement to permit the movement of the prongs 27 in a vertical direction an amount substantially equal to, or slightly greater than the length of the prongs. A 5 spring pressed detent, shown at 45 in Fig. 4, may be arranged in a housing 46 secured to the handle 38, and a pair of depressions 47 may be formed in the plate 23 to receive this detent to hold the handle in its extreme 10 positions.

In operation, the lever 38 is first placed in the position shown in Fig. 1, so that the prongs 27 which point downwardly are in their highest position, and those which point 15 upwardly are in their lowest position. A surface of the material to be sliced is then pressed against the points of these prongs and held in this position with sufficient pressure to permit the prongs to enter the material when they are shifted in the direction in 20 which they are pointed. The lever 38 is then moved to its other extreme position and during this movement the prongs 27, being inclined to the surface of the material, will 25 enter the material at an oblique angle and so draw the material firmly against the faces of the plates 26. Since alternate rows of prongs 27 move in opposite directions, the material itself will be held from shifting its 30 position since the force exerted upon it by the prongs 27 is divided, half of the force acting in one direction and half in the other. When the material has been thus clamped to the holder, it will be firmly held 35 in place and will resist a force tending to move it in any direction. The machine is then operated to form the projecting portion of the material into slices, the last cut being taken on a plane just sufficiently removed 40 from the surface of the plates 26 to avoid contact between the slicing knife and the prongs 27. This will leave the last slice of material held by the prongs 27 against the faces of the plates 26, and it is only necessary 45 to return the handle 38 to its initial position to withdraw the prongs from this last slice, which may be disposed of and utilized in the same manner as the other slices.

The form of the device shown in Figs. 5, 50 6 and 7 differs from that already described in that a cover plate 50 is placed over the front surface of the holder and is provided with a series of openings 51 through which the prongs 27 project. This cover plate 50 55 serves as a stationary back plate against which the material is drawn by the prongs 27 during the clamping operation. The same form of operating handle may be employed in connection with this modification 60 as is used in the one previously described, but I have shown instead a slightly modified form of the lever 38 which is provided with cam slots 52 arranged to engage pins 53 which project from the bars 28 and 30. The 65 pivotal support for the lever 38 is carried by

a bracket 54 secured to the frame by lag screws 55. This form of operating handle permits the application of the force to the bars 28 and 30 to be made directly at their middle portions, and the use of cam slots in 70 the place of links for operating the bars renders unnecessary the detent for holding the handle 38 in its positions.

I claim:

1. A device for holding material to be 75 sliced, comprising a plurality of sets of oppositely inclined prongs, and means for relatively moving said sets of prongs in opposite parallel directions to cause said prongs to penetrate the material to be held. 80

2. A device for holding material to be sliced, comprising an upright frame, a set of prongs carried by said frame and arranged at a fixed oblique angle thereto, a second set of prongs carried by said frame 85 and arranged at a fixed oblique angle thereto and having their points inclined in a direction opposite to that of the first-mentioned set of prongs, and means for simultaneously moving said sets of prongs in opposite parallel directions to cause said prongs to enter material to be held. 90

3. A device for holding material to be sliced, comprising a frame, prongs carried by said frame and inclined outwardly and 95 downwardly therefrom, other prongs carried by said frame and inclined outwardly and upwardly therefrom, and mechanism for moving each of said sets of prongs vertically in the direction of their inclination to 100 cause said prongs to enter material to be sliced.

4. In combination, a plurality of bars arranged side by side, pointed prongs carried by said bars for engaging material to be 105 sliced, and means for shifting said bars longitudinally to cause said prongs to enter said material.

5. In combination, a plurality of bars arranged side by side, prongs carried by said 110 bars for engaging material to be sliced the prongs on adjacent bars being inclined in opposite directions to one another, and mechanism for shifting said bars longitudinally, said mechanism being arranged to 115 move each bar in a direction opposite to the movement of the next adjacent bar.

6. In combination, a frame, a plurality of bars carried by said frame and arranged side by side therein to form a substantially continuous surface, prongs carried by said bars for engaging material to be held, the prongs of alternate bars being inclined away from said surface in one direction while those of the alternating bars are inclined away from 120 the surface in the opposite direction, and means for shifting the bars in sets corresponding to the direction of the inclination of their prongs, to cause said prongs to 125 enter material to be sliced. 130

7. In combination, a plate having a plurality of openings therein, prongs arranged to project through said plate at an oblique angle to the surface thereof, and means for shifting said prongs relative to said plate in a direction parallel thereto to cause said prongs to engage material to be sliced.
8. In combination, a plate having openings therein, prongs projecting through said plate and arranged at an oblique angle to the face thereof, some of said prongs being inclined in one direction and others of said prongs being inclined in an opposite direction relative to said surface, and means for shifting said prongs in the direction of their inclination and parallel with said plate to cause said prongs to enter material to be sliced and to draw said material against the surface of said plate.
9. A device for holding material to be sliced, comprising a frame having a plurality of sets of oppositely inclined prongs thereon, and mechanism for moving the prongs of one of said sets relatively to the prongs of another while maintaining corresponding portions of the prongs of the set thus moved in a fixed plane relative to the prongs of the other set.
10. A device for holding material to be sliced, comprising a frame having one face thereof arranged to be presented to material to be sliced, a plurality of prongs arranged at an oblique angle to said face, a portion of said prongs being inclined to said face in a direction opposite to others of said prongs, and means for shifting said prongs relative to one another in a direction parallel to said face.
11. In testimony whereof I have signed my name to this specification on this 25th day of June, A. D. 1917.

CORNELIS F. M. VAN BERKEL.
